JAMES WHITEHEAD, OF OTLEY, ENGLAND

ANTIBALLOONING ARRANGEMENT FOR CAP AND RING SPINNING, DOUBLING,
TWISTING, AND LIKE MACHINES

Application filed December 19, 1928, Serial No. 327,089, and in Great Britain December 22, 1927.

This invention relates to the production of anti-balloon devices, which are used in connection with cap and ring spinning, doubling, twisting and like machines of that type of said devices which may be adjusted in the desired position relatively to the ring rail of a ring spinning or like machine or to the lifter rail of a cap frame and which may be applied either to new or to existing machines, and my said invention consists in the employment of a manually actuated shaft which I mount to extend lengthwise the machine and I arrange same to rotate on bearings fixed to the stationary framework of the machine in order that by pinions fixed on said shaft being made to engage with racks attached to a rail carrying the anti-balloon devices the whole series of said devices may be made to occupy and be adjusted in a higher or lower position as occasion may require and as is hereinafter explained.

In the accompanying sheets of drawings which are illustrative of my invention:—

Fig. 1 is a front elevation of sufficient of a cap spinning frame to show the application of my improved devices. My said devices are shown in their lowest positions where they are adjusted during the process of doffing.

Fig. 2 is a similar view to Fig. 1 but shows my said devices approximately in the right position that they occupy during the spinning and like operations.

Fig. 3 is a plan, drawn to an enlarged scale, showing my improved device as mounted in position surrounding a cap.

Fig. 4 is a plan, showing the mechanism by which I am enabled to raise and lower or adjust my said improved devices.

Fig. 5 is a side elevation of the parts shown by Fig. 4, as seen looking from left to right of said figure.

Fig. 6 is an end elevation showing means whereby I am enabled to operate the devices shown by Figs. 4 and 5.

Fig. 7 is a drawing of a single cap (made to an enlarged scale as compared with Figs. 1 and 2) with my improved device mounted in position in connection therewith.

Fig. 8 shows my improved device as used in connection with a ring spinning machine in which the ring rail is stationary while the bobbin upon which the yarns are being wound has rising and falling movements imparted to it. 55

Fig. 9 shows a modified form of one of the devices shown by Fig. 3.

Figs. 10 and 11 are end and front views respectively of a modified form of gearing 60 for operating the parts hereinafter described.

A indicates the end frame of the machine, B the longitudinal rails, C the lifter plate and D the caps of a cap spinning and like machine. 65

In carrying my invention into effect I make use of a known form of anti-balloon device a which is formed of round metal or wire and which is bent in the shape of a spiral as is shown by Figs. 3 and 7. The end $2b$ of 70 the circular part a of the anti-balloon device is extended in order to facilitate threading as is well known while the other end $2c$ extends from the part $2a$ so that its outer end $2d$ may be screw threaded in order that by 75 the fixing nuts h and h' it may be fixed to the longitudinal bar b which extends lengthwise the spinning frame. Or the end $2c$ may be of tapering form and made to terminate in the position shown by Fig. 9. 80

The bar b is fixed upon vertical racks k which are sufficient in number to support said bar b throughout the whole of its length. The racks k mesh or gear with pinions m which correspond in number with the number 85 of the racks k and said pinions m are fixed upon a horizontal shaft p which also extends lengthwise the machine so that at its outer end and beyond the end frame A it may have fixed upon it a gearing wheel which meshes 90 with a pinion p^2 fixed to the ratchet wheel s that is engaged with by a pawl s^1 so that same may be retained in position as will be understood. The ratchet wheel s and pinion p^2 are fixed upon the hub of the hand wheel 95 p^4 so that all the three of them run loosely upon the stud p^3 . By the employment of the devices described the attendant may rotate the hand wheel p^4 so as to operate the shaft p in order that the pinions m may raise the 100

racks *k*, and therefore the bar *b*, or lower same as may be desired while when in position the pawl *s*¹ will prevent the descending of the rail *b* until the attendant again releases same in order to rotate the hand wheel *p* in the opposite direction for lowering the rail *b*.

Instead of the wheels *s*, *p*², I may make use of a worm wheel *p*⁶ and a worm *p*⁷ as shown by Figs. 10 and 11. In this case the wheel *p*⁶ is fixed upon the shaft *p* while the worm *p*⁷ which gears with it is fixed upon the shaft *p*⁸ which is mounted in bearings *p*⁹ and made to extend towards the front of the machine so that the hand wheel *p*¹⁰ may be fixed to the end thereof. By these means the adjustment of the several parts in their respective positions may be readily effected while by the worm element they may be retained in any of the positions that they are made to occupy.

As is shown by Fig. 1 of the drawings the attendant, prior to the process of doffing, and after arresting the motions of the machine, will lower the devices *a* in order to leave the caps *D* clear and free so that the attendant may handle same without interference by any of my devices, while the same adjusting mechanism enables the attendant, as is before stated, to adjust the rail *b* in any desired position lengthwise said caps *D*.

Although I have hereinbefore described my improved device as being applicable for use in connection with cap spinning frames the same may also be made use of in ring spinning machines when such machines have the ring rail fixed or stationary and wherein the bobbin *f* and its spindle are raised and lowered to carry out the building operations. In the said type of machine my device *a* may be mounted in the position relative to the ring rail somewhat as shown by Fig. 8.

Such being the nature and object of my said invention what I claim is:—

In anti-ballooning mechanism for cap or ring spinning machines, the combination with a series of anti-ballooning devices corresponding in number with the number of spindles in the machine, a rail or bar in said machine upon which said devices are adjustably mounted, racks supporting said longitudinal bar, guiding devices for said racks, a shaft extending lengthwise the machine, pinions on said shaft engaging the racks, a toothed wheel fixed on said shaft, a pinion engaging said toothed wheel, a hand wheel for actuating the last said pinion, a ratchet wheel fixed to the hand wheel, and a ratchet for engaging said ratchet wheel.

JAMES WHITEHEAD.
